UNITED STATES PATENT OFFICE

2,456,278

ACETYLENE GENERATOR

George L. Hill, Houston, Tex.

Application January 5, 1945, Serial No. 571,456

8 Claims. (Cl. 48—53)

1

This invention relates to gas generators, and more particularly it is of utility in the field of generation of acetylene gas wherein a solid, gas-generating material, calcium carbide, is dropped from a dry chamber into a fluid-containing, gas-generating chamber.

The primary object of the invention is to provide a gas generator having new and useful improvements for charging the generator with the solid, gas-generating material and for introducing the material of the charge to the gas-generating chamber.

An object of the invention is to provide a gas generator having a hopper closure constructed to facilitate the recharging of the device.

Another object is to provide a positive closure for the generating chamber to avoid the entrance of atmosphere thereto during the recharging of the device.

A further object is to provide a gas generator including a diaphragm which is attached to the carbide releasing valve, such diaphragm having a central opening through which the gas-generating material passes.

A further object is to provide a pressure chamber above the diaphragm for controlling the valve for admitting gas-generating material to the generating chamber.

A further object is to provide a gas generator comprising a carbide releasing valve and a closure valve for the generating chamber and co-operating means for restraining the former from opening when the latter is closed.

The foregoing are primary objects which will, together with further objects, be more fully apparent from the following description taken in connection with the accompanying drawings, in which:

Fig. 1 is a vertical sectional view through a generator embodying the invention;

Fig. 2 is a plan view taken on line 2—2 in Fig. 1;

Fig. 3 is a sectional view taken on line 3—3 in Fig. 1; and

Fig. 4 is a partial section taken on line 4—4 in Fig. 1.

In effectuating the objects of the invention, the form shown in the drawings comprises a hopper 1, which is provided with a flange 2 at its lower end for attachment to a complementary flange 3 on the generating chamber 4 by means of bolts 5 passing through the flanges. Interposed between the flanges 2 and 3 is the peripheral portion of a closure member 6 for the generating chamber, such closure being designed to

serve a purpose that will be more fully described.

It is intended that the hopper 1 shall receive a charge of gas-forming material, such as calcium carbide, used in the generation of acetylene, and the construction and operation of the device shall be such that the calcium carbide shall be admitted to the chamber 4 at a rate to provide an adequate amount of gas at a desired pressure. To this end the upper end of the hopper 1 is constructed in a manner to facilitate the admission of a charge of calcium carbide to the interior of the hopper and thereafter to close the hopper against the pressure of the gas generated within the generating chamber 4. The upper end 10 of the hopper 1 is reversely flanged at 10 and the upper face thereof is grooved to receive a gasket ring 11 for engagement by the cover 12 hinged at 13 to the exterior of the hopper.

The reverse flange 10 provides an external annular groove 14 engageable by the hooked ends 15 of the arms 16, which are attached through slotted pivots 17 to paired ears 18 on the cover 12. The inner ends of these arms terminate in pivots 19 in collar 20, which is threaded internally to receive the set screw 21 which bears upon the cover 12 to exert the desired pressure between the cover and the gasket 11 to assure a seal with the top of the hopper. The hinge 13 on the cover permits the cover and associated securing elements to be swung to one side during the time the hopper is being recharged with the gas-generating material.

The bottom of the hopper 1 is in the form of a truncated cone, which provides an opening 30 which is normally closed by a valve 31 having a stem 32 extending upwardly through guide members 33 and 34. A compression spring 35 surrounds the stem 32 and bears upon the member 33 and the collar 36, the latter being secured to the stem. By means of this structure, as above indicated, the valve is normally held in closed position so that gas-generating material placed within the hopper 1 is retained therein.

The lower end of the hopper wall is flanged inwardly and upwardly at 40 and is provided with inwardly extending ears 41 adjacent its upper end. These ears serve to limit the upward travel of a diaphragm and bellows assembly 42, which comprises a securing plate 43 and screws 44 which clamp the periphery of the diaphragm 45 to the bottom of the hopper structure. The inner periphery of the diaphragm 45 together with the lower end of a bellows 46 are clamped together between an annulus 47 and the flange of 55 the collar 48, through which bolts 49 pass.

To effect operation of the valve 31 by movement of the diaphragm assembly 42, a bar 50 is attached to the assembly by two of the bolts 49. This bar has a central opening to receive the downwardly extending portion of the valve stem 32, which is secured thereto by means of the nuts 51.

Below the diaphragm assembly 42 the stem 32 is provided with a collar 60, against which a yoke 61 of actuating rod 62 bears. This rod extends outwardly through a stuffing gland 63 to the exterior of the generating chamber 4 so that manual operation may be effected to move the valve 31 downwardly and initiate the passage of material from the hopper 1 to the generating chamber 4.

The closure member 6 has a threaded boss 70 at its lower end, and a plug valve 71 is attached thereto. The surface of the plug 72 of this valve is juxtaposed to the lower end of the valve stem 32 so that the valve 31 is restricted against downward movement when the valve 71 is closed. A valve operating rod 73 is attached to the plug 72 and passes through gland 74 to the exterior of the generating chamber 4.

A nipple 75 is attached to the plug valve 71 at its lower end. A knocker 76 extends inwardly from gland 77 so that impacts may be imparted to the valve assembly to dislodge any particles of gas-generating material that may become lodged thereon.

In order to provide automatic operation of the device of the invention, a by-pass 80 is provided from the generating chamber 4 to the enclosure above the diaphragm 45. This by-pass is provided with a check valve 81, which admits gas to the enclosure, but prevents the return of the gas to the chamber 4 when the pressure within the latter decreases. When the desired pressure is established within the closure above the diaphragm 45, a hand-operated valve 82 in the by-pass 80 is closed so that the quantity of entrapped gas above the diaphragm 45 remains constant. By means of these co-operating structures, automatic operation is obtained, as will more fully appear from the description of the mode of operation of the device. In describing the operation, it will be assumed that the hopper 1 is substantially empty and that the pressure within the generator chamber 4 is the same as that above diaphragm 45, so that the valve 31 is closed under tension of the spring 35. The stem 32 of the valve 31 is thus in its uppermost position and the valve 71 can be closed, as shown in Fig. 1, whereby the chamber 4 is sealed. While it is intended that the valve 31 shall be capable of maintaining a seal with the bottom of the hopper 1, the closure of the valve 71 assures that there shall be no leakage of gas during the recharging of the hopper. It is to be understood however, that suitable pressure line taps (not shown) are provided from chamber 4, and that gas may be used therefrom under accumulated pressure during the recharging operation.

If the pressure in the chamber 4 has fallen below that in the enclosure above diaphragm 45 when recharging is necessary, the valve 31 will, of course, be held open because of the differential pressure above and below the diaphragm. Under such circumstances gas is withdrawn from above the diaphragm by opening the valve 83, whereby sufficient gas escapes that the valve 31 is permitted to close. The valve 71 can then be closed and recharging initiated in the manner above indicated.

After the valve 71 is closed, the cover 12 is released by loosening the set screw 21. The cover is then swung outwardly on its hinge 13, whereupon a quantity of the gas-generating material is readily placed within the hopper 1. The cover is then replaced and screw 21 is tightened to reseal the hopper.

If working pressure is maintained within the enclosure above diaphragm 45, automatic operation of the device is thereafter resumed as soon as valve 71 is opened. This will permit the valve 31 to move downwardly and admit material from the hopper to the chamber 4 as the lower end of the valve stem 32 is permitted to move into the opening in the plug 72 due to an excess of pressure above the diaphragm. Obviously, the valve 31 will close as soon as the pressures above and below the diaphragm are substantially equal.

If gas is withdrawn through the valve 83 preliminary to recharging or the device is to receive its initial charge, the valve 82 will be opened and valve 31 will be moved downwardly by means of the operating rod 62. When the desired pressure is generated within the device, the valve 82 is again closed and thereafter automatic operation continues.

In the event that particles of the gas-generating material become lodged in or upon the valve 71, it is, of course, understood that necessary vibration to dislodge such particles can be effected by actuating the knocker 76.

The invention claimed is:

1. A gas generator comprising a hopper having an opening in the bottom thereof, a valve in said opening, means normally holding said valve in closed position, a generating chamber below said hopper, diaphragmatic means forming a partition below said hopper and carrying said valve, and means normally maintaining a predetermined pressure between said diaphragmatic means and said hopper.

2. A gas generator comprising a hopper having an opening in the bottom thereof, a valve in said opening, means normally holding said valve in closed position, a generating chamber below said hopper, diaphragmatic means forming a partition below said hopper and carrying said valve, means normally maintaining a predetermined pressure between said diaphragmatic means and said hopper, and means for reducing the pressure within the enclosure above said last mentioned means to close said valve during recharging of the hopper.

3. A gas generator comprising a hopper having an opening in the bottom thereof, a valve in said opening, a generating chamber below said hopper, a diaphragm assembly sealably attached to the bottom of the hopper about said opening and forming an enclosure, a connection between said valve and said assembly, and means for maintaining a predetermined quantity of pressure fluid within said enclosure.

4. A gas generator comprising a hopper having an opening in the bottom thereof, a valve in said opening, a generating chamber comprising a closure including a second valve operable to seal said chamber, said closure co-operating with said hopper to form an enclosure therebetween, a diaphragm forming a partition within said enclosure, and means for admitting pressure from the chamber to the space above said diaphragm.

5. A gas generator comprising a hopper having an opening in the bottom thereof, a valve in said opening, said valve including a stem extending

downwardly therefrom, a generating chamber, a closure for said chamber, said closure having an opening in alignment with said stem and valve, and means in said last mentioned opening proximate said stem adapted, when closed, to resist opening of the first mentioned valve.

6. A gas generator comprising a hopper having an opening in the bottom thereof, a downwardly opening valve in said opening, spring means tending to hold said valve in normally closed position, a generating chamber below said valve, closure means therefor forming an enclosure between the hopper and chamber, a diaphragm forming a partition in said enclosure, means interconnecting said diaphragm and said valve, and means for admitting gas under pressure from the generating chamber to the space above said diaphragm whereby gas within said space functions to open said valve upon a decrease in pressure within the generating chamber.

7. A gas generator comprising a hopper having an opening in the bottom thereof, a downwardly opening valve in said opening, spring means tending to hold said valve in normally closed position, a generating chamber below said valve, closure means therefor forming an enclosure between the hopper and chamber, a diaphragm forming a partition in said enclosure, means interconnecting said diaphragm and said valve, means for admitting gas under pressure from the generating chamber to the space above said diaphragm whereby gas within said space functions to open said valve upon a decrease in pressure within the generating chamber, and additional manually operable means for opening said valve to release material from the hopper to the generating chamber.

8. A gas generator comprising a hopper having an opening in the bottom thereof, a downwardly opening valve in said opening, spring means tending to hold said valve in normally closed position, a generating chamber below said valve, closure means therefor forming an enclosure between the hopper and chamber, a diaphragm forming a partition in said enclosure, means interconnecting said diaphragm and said valve, means for admitting gas under pressure from the generating chamber to the space above said diaphragm whereby gas within said space functions to open said valve upon a decrease in pressure within the generating chamber, and means for releasing gas from the space above the diaphragm to permit said valve to close.
